AUTOMOBILE LICENSE PLATE HOLDER

Gerald S. Rothman, New York, N. Y.

Application April 27, 1950, Serial No. 9,513

Term of patent 14 years

(Cl. D14—6)

To all whom it may concern:

Be it known that I, Gerald S. Rothman, a citizen of the United States, residing in New York city, in the county of Queens and State of New York, have invented a new, original, and ornamental Design for an Automobile License Plate Holder, of which the following is a specification, reference being had to the accompanying drawing, forming part thereof.

Fig. 1 is a front perspective view of an automobile license plate holder, showing my design;

Fig. 2 is the rear view of the automobile license plate holder shown in Fig. 1;

Fig. 3 is a cross sectional view of the automobile license plate holder taken on lines 3—3 of Fig. 2.

The drawing has been shaded to show contrasting appearance. The dotted lines appearing on Fig. 1 are for illustrative purposes only.

I claim:

The ornamental design for an automobile license plate holder, substantially as shown and described.

GERALD S. ROTHMAN.
